CLAIM

The ornamental design for a spraying device, as shown and described.

DESCRIPTION

FIG. 1 is a front perspective view of a spraying device and showing our new design;

FIG. 2 is a rear perspective view thereof;

FIG. 3 is a left side view thereof;

FIG. 4 is a right side view thereof;

FIG. 5 is a top view thereof;

FIG. 6 is a bottom view thereof;

FIG. 7 is a front view thereof;

FIG. 8 is a rear view thereof; and,

FIG. 9 is a perspective view of the spraying device of FIG. 1, shown in a position of use attached to an unclaimed bottle drawn in broken lines.

The broken lines shown in FIGS. 1–9 depict portions of the spraying device that form no part of the claimed design. The broken lines illustrating a bottle in FIG. 9 only depicts environment and forms no part of the claimed design.

1 Claim, 5 Drawing Sheets
